UNITED STATES PATENT OFFICE.

JOHN R. MARDICK, OF NEW YORK, N. Y., ASSIGNOR TO UNIVERSAL OIL PRODUCTS COMPANY, OF CHICAGO, ILLINOIS, A CORPORATION OF SOUTH DAKOTA.

METHOD OF CRACKING OILS.

Application filed May 5, 1923. Serial No. 637,012.

This invention relates to the treatment of petroleum oils in order to improve the yield and quality of the distillates obtainable therefrom, and particularly from petroleum residues, and has for its principal objects the expeditious and economical production of high test distillates, such for example as gasoline, kerosene, lubricating oils and the like from petroleum residues resulting from the removal of the natural gasoline and kerosene from crude petroleum oil as well as further objects as will more in detail and at length appear in the following description.

It is well known that elements in their nascent or freshly liberated condition are far more active than the same elements in their ordinary or non-nascent condition. The crux of my invention consists in the utilization of chlorine which has been previously rendered active so as to substantially correspond to chlorine in a nascent condition, while at the same time avoiding the presence of objectionable elements, such as compounds of aluminum for example, which result from the well-known catalytic conversion of high boiling petroleum oils into lower boiling point petroleum oils by the employment of aluminum chloride.

My investigations have lead to the discovery that ordinary chlorine, for example such as obtained by the electrolysis of brine is, when properly activated in the manner hereinafter described, peculiarly suited for employment in the production of "sweet", resinous and gum-free gasoline, kerosene, lubricating oil and like relatively low boiling point distillates from high boiling point petroleum residue.

In the accompanying drawing, I have illustrated an apparatus well known in the art suitable for activating the chlorine, although other suitable apparatus may be employed in lieu thereof, the view shown being a vertical section.

Referring to the drawings and the construction shown therein, the reference numeral 1 designates the metallic casing of a reaction chamber *a*, in which chamber is mounted a discharge electrode 2, which is suspended from an insulated support 3 that is in turn connected to a high potential circuit, such as is commonly employed for the production of an electric corona. At the bottom of said casing I provide an inlet 4 for the admission of dehydrated, and pref-

erably preheated, chlorine and at the top of said casing is an outlet 5 which is adapted to conduct the activated chlorine obtained in said apparatus to a still or absorption tower wherein the activated chlorine is brought into intimate contact with dehydrated oils or oil residues, also preferably preheated as hereinafter described, which it is desired to subject to the action of such activated chlorine.

In carrying out my invention I preferably proceed as follows:

A petroleum residue such as gas-oil having a boiling point of, say, 250° C. and upwardly, which is obtained by the preliminary heating or "topping" of crude petroleum to remove moisture and the lighter distillates therefrom that are natural to the petroleum is heated to a temperature of, say, 300° C. and while so heated is intimately mixed in any desired manner with activated chlorine prepared preferably in the manner herein described. The supply of chlorine, if too rapid, would result in the formation of gummy, resinous solids which will not only interfere with the operation and the yield obtainable thereby, but will impart objectionable properties to the light distillates resulting from such treatment. On the other hand, if the supply of chlorine is too slow or insufficient, the yield of light distillates will be objectionably low. Accordingly the rate of supply of the chlorine to the heated oil should be so regulated that the light distillates, particularly such as gasoline, kerosene and even lubricating oils which are obtained from the high boiling point residue will be substantially free from gums and resin, but not so low that the quantity of light distillates boiling below 230° C. will be insufficient for the satisfactory commercial operation of the process. A suitable proportion of chlorine activated in the manner hereinafter described, for admixture with gas-oil obtained from such oils for example as Pennsylvania and Louisiana crude oils (paraffin type) or Oklahoma crude oils (paraffin and asphaltic types) is from one-half to one percent of chlorine upon the weight of the oil residues treated, the rate of supply being, however, in all cases primarily determined by the aforesaid characteristics and yield of the lower boiling point distillates. Preferably the chlorine is supplied at about five pounds pressure per square inch.

The admixture of the chlorine and the hot oil residue can be accomplished either by causing the chlorine, previously dried, as hereinafter described, to bubble through a body of heated gas-oil or other suitable residue free from water or the said heated oil residue and such chlorine can be brought together in a tower, filled with inert material, in which the oil residue flows downwardly from the top and the chlorine flows upwardly in the opposite direction being brought at intimate contact with each other by passage over the inert material, which latter may also be suitably heated if desired. In certain cases it may be also desirable to effect the mixture of the activated chlorine with oil vapors resulting from the heating of such oil residue, such mixture preferably being also effected in a tower filled with heated inert material.

My activated chlorine which is suitable for utilization in the aforesaid process is prepared by dehydrating ordinary chlorine which is either obtained by the electrolysis of brine or purchased in a compressed condition, such dehydration being effected by causing the same to pass through concentrated sulphuric acid of 60° to 66° Bé. strength preferably and also through solid calcium chloride, or in any other satisfactory manner. The object of such dehydration of both the chlorine as well as the oil residue is to prevent the destruction of the activated chlorine by interaction of such water with consequent great reduction in yield of lower boiling point distillates obtained by the operation of the process.

The activation of such previously dried chlorine is effected by causing the passage thereof through an electrical apparatus such as an electrical ozonizer or preferably through an electrical apparatus in which the chlorine is subjected to the activating influence of attenuated arcs or sparks of the violet ray type such as is commonly employed in electrical precipitation by the well known Cotrell process or by the well known corona discharge apparatus, such as disclosed in the patent to W. A. Schmidt and E. R. Wolcott No. 1,307,930 of June 24, 1919 and the patent to W. A. Schmidt and G. C. Roberts No. 1,343,482 of June 15, 1920.

Chlorine activated as aforesaid is then admixed with the oil residues, or the vapors thereof in the manner hereinbefore described and preferably such chlorine is preheated immediately before being admixed with such oil residues or the vapors thereof, although when so preheated care must be taken that the temperature does not exceed that at which the activity of the chlorine will be destroyed.

While I preferably employ about five pounds of pressure in operating my preferred process, I may, if desired, operate the same under several atmospheres of pressure, say,

two or three atmospheres or higher if desired, although the mechanical objections to operating under increased pressures will usually offset any possible advantage to be gained thereby.

One of the advantages of my improved method is that the same may be operated in ordinary tubular stills without objectionable corrosion thereof, in view of the fact that the oil residue and the chlorine are in a dehydrated condition, and furthermore the resultant coke obtainable by the operation of this process is, unlike that obtainable by catalytic conversion processes employing aluminum chloride, free from inorganic impurities such as aluminum oxide, and therefore is peculiarly valuable for metallurgical and electrochemical purposes wherein such a carbon product would, because of its freedom from impurities and its other desirable properties, be useful and essential.

Not only is my process peculiarly adapted for the treatment of oil residues of the paraffin type, but even oil residues of the asphaltic type and particularly of the asphaltic and paraffin type, as well as oil residues containing substantial quantities of sulphur, can be materially improved by treatment in accordance with my process.

The gasolene, kerosene and lubricating oils obtained from the treatment of suitable petroleum residues by my improved process and particularly those obtainable from the treatment of Pennsylvania and Louisiana petroleum residues are relatively free from unsaturated hydrocarbons and will not form any appreciable amount of tarry substances when treated with fuming sulphuric acid in the manner customary in treating such products in order to remove unsaturated hydrocarbon therefrom. In fact, gasolene obtainable by my improved process can be refined without the employment of sulphuric acid as it merely requires washing with alkali in order to make a highly satisfactory product. Furthermore, such gasolene, kerosene and lubricating oils obtained through the employment of my process are, as heretofore stated, peculiarly free from resins and gums and furthermore owing to the absence of objectionable, odoriferous, unsaturated hydrocarbons in any large quantity are peculiarly "sweet" and water-white or transparent.

The unusually effective cracking accomplished by the herein-described treatment of oils can best be explained as an electron phenomenon. For example, it is well known that atoms consist of even smaller particles which are termed electrons and the latter when the atoms have been freshly liberated from their combinations are highly charged with electricity. On standing, however, the electrons tend to regroup themselves with the consequence that the electrical charges carried thereby become neutralized or changed in

polarity and thereby the atomic and molecular activity of any particular element under observation becomes materially impaired or lessened.

- 5 In the case of chlorine, it has been established that two different kinds of atoms exist each having characteristic groupings of electrons and atomic weights. When electrically activated through the influence of a high potential electric current, however, it is believed that there is a substantial energizing of the atoms by causing a movement of the electrons from the inner to outer orbits with the possible consequence of a radical regrouping of 15 the electrons or even the atoms themselves in a manner somewhat akin to the change produced by an ozonizing electrical current upon oxygen. The foregoing explanation accounts for the fact that the inactive chlorine atoms either become highly active or have 20 their original activity restored upon being activated in the manner herein described.

My improved process may either be conducted as a continuous or an intermittent process and may be applied to other oil residues than those boiling upwardly from 250° C., it being especially serviceable for cracking kerosene into gasoline hydrocarbons in those cases when the latter can be disposed of to better advantage than the kerosene.

Preferably I employ reflux condenser of the type commonly employed in this art and return to the still the vapors condensing below certain desired temperatures for further treatment. Ordinarily a period of treatment of from 24 to 36 hours will suffice to effect the conversion within economic limits of cost of substantially all of the convertible 40 portions of the oil treated to the lower boiling point distillates.

In those cases where it is merely desired to effect the improvement of the oil treated, as low as $\frac{1}{10}$ th of a percent of activated chlorine, based on the weight of the oil, will be found to be useful, but for the production of low boiling point hydrocarbons, particularly those of the gasoline type, I find it advisable to employ at least $\frac{1}{4}$ th of 1% of activated chlorine and preferably between $\frac{1}{2}$ of 1% and 1% as previously stated. In practically no instance, regardless of the oil treated, should the amount of activated chlorine exceed 2% of the weight of the oil treated. Furthermore, the temperature of treatment will likewise depend upon the character of the distillates desired. For example, for improving lubricating oils without effecting undue cracking thereof, a low temperature of treatment is desirable, i. e. approximately between 60° C. and 75° C., whereas, if a high yield of low boiling point hydrocarbons such, for example, as hydrocarbons within the range of gasoline (i. e. those having a boiling point up to approximately 230° C. is desired, it is

important that the temperature employed should more closely approximate the boiling point of the residue under the pressure at which it is subjected in the treatment.

Depending upon the character of the residues employed, it is possible to obtain an amount of low boiling point hydrocarbons of the gasoline range in amounts ranging from 15%, and in some instances up to even 45% of the weight of the oil residue treated.

As is evident from the foregoing description, my improved process possesses the peculiar advantage over the well known catalytic conversion processes employing aluminum chloride of avoiding the necessity of removing aluminum chloride from the coke-containing sludge remaining in the still after the removal of the gasoline, kerosene and like burning oil distillates, in order to produce high quality lubricating oils therefrom. Notwithstanding moreover, the fact that in such aluminum chloride process, the aluminum chloride may be recovered to a substantial extent, nevertheless, it will be found that the employment of activated chlorine, in the manner herein described, is far more economical and produces higher grade products than it is possible to obtain by such prior methods utilizing aluminum chloride.

While I have disclosed the employment of electrically activated chlorine because of its cheapness, the substitution therefor of the well known chemical equivalents is equally within the scope of the appended claims.

Having thus described my invention, what I claim is:

1. The method of cracking oil which comprises heating a high boiling point oil, and subjecting such oil to the action of previously electrically activated chlorine in the absence of sufficient moisture to materially interfere with such cracking operation, and then collecting the relatively low boiling point distillates obtained by such treatment.

2. The method of cracking high boiling point petroleum oil in order to obtain therefrom gasoline hydrocarbons, including those of the gasoline range, which comprises subjecting petroleum oil having a boiling point in excess of 230° C. to the action of free chlorine gas introduced from an external source into such oil while in the absence of sufficient moisture to seriously interfere with the cracking operation, the chlorine when so introduced being in a highly active state due to the energizing of the atoms thereof while in substantially anhydrous condition and then recovering the low boiling point hydrocarbons resulting from such treatment.

3. In the process of cracking petroleum oil, the step which consists in subjecting a petroleum residue having a boiling point in excess of 230° C. to the action of previously activated chlorine gas while in the absence of sufficient moisture to seriously interfere with the crack-

ing operation, said chlorine gas being introduced into said oil residue in a gaseous condition.

4. In the process of cracking petroleum, 5 the steps which consist in subjecting dehydrated residual petroleum oils to the action of activated chlorine substantially free from in- 10 organic chlorine-compounds foreign to such oil in its untreated condition, the time of treat- 15 ment, the temperature of treatment and the amount of such chlorine employed being suffi- 20 cient to effect the conversion of such residue into low boiling point hydrocarbons to the extent of at least 25% of the weight of the 25 residue treated.

5. In the process of cracking petroleum oil, 20 the step which consists in subjecting a high boiling point petroleum oil residue to the action 25 of previously activated chlorine gas while 30 in the absence of sufficient moisture to seriously interfere with the cracking operation and while maintaining the mixture at an elevated temperature sufficient to effect the conversion of a large portion of such oil treated 35 into low boiling point products.

6. In the process of cracking petroleum oil, 35 the step which consists in subjecting a petro- 40 leum residue substantially free from hydro- carbons having boiling points below 230° C. while 45 maintained at a temperature in excess of 200° C. to the action of previously electric- 50 ally activated chlorine gas while in the ab- 55 sence of sufficient moisture to seriously inter- fere with the cracking operation.

35 7. The method of cracking high boiling point petroleum oil in order to obtain there- 40 from gasolene hydrocarbons, including those of the gasolene range, which comprises sub- 45 jecting anhydrous petroleum oil having a 50 boiling point in excess of 230° C. to the action 55 of free chlorine gas introduced from an exter- 60

nal source under a super atmospheric pressure 45 into such oil, the chlorine so introduced being in a highly active state due to the activation thereof while free from sufficient water to prevent effective activation thereof by a high potential electric current and then recovering the low boiling point hydrocarbons resulting from such treatment.

8. In the process of improving residuum 50 petroleum oil, the step which consists in sub- 55 jecting a petroleum residue substantially free from hydrocarbons having boiling points below 230° C. and while maintained at a temper- 60 ature in excess of 60° C. to the action of previ- 65 ously electrically activated chlorine gas while in the absence of sufficient moisture to seri- 70 ously interfere with the cracking operation.

9. The method of cracking high boiling 65 point petroleum oil in order to obtain there- 70 from gasolene hydrocarbons, including those of the gasolene range, which comprises sub- 75 jecting anhydrous petroleum oil having a boiling point in excess of 230° C. to the action of free chlorine gas in the proportion of be- 80 tween 1/4% and 2% by weight of the petro- 85 leum oil treated and while maintaining mix- 90 ture at a temperature not substantially less than the boiling point of the petroleum oil treated, such chlorine gas being introduced into said oil under a super atmospheric pressure from an external source into the oil treated while in a highly active state due to the activation thereof while in a sufficiently anhy- 95 drous condition to permit of effective activation thereof by a high potential electric current and then recovering the low boiling point hydrocarbons resulting from such treatment.

Signed at New York city in the county of New York and State of New York this 1st day of May, 1923.

JOHN R. MARDICK.
